FIG. 1

FIG. 2

FIG. 3

FIG. 4

FIG. 1 is a perspective view of a combined telephone handset and desk stand showing my new design;

FIG. 2 is a top plan view, to an enlarged scale, of the combined telephone handset and desk stand shown in FIG. 1;

FIG. 3 is a side-elevational view of the combined telephone handset and desk stand shown in FIG. 2; and

FIG. 4 is an end view of the combined telephone handset and desk stand shown in FIG. 3.

The undisclosed opposite side of the combined telephone handset and desk stand is plane unornamented.

The dominant features of my design reside in the portions shown in solid lines on the drawing.

I claim:

The ornamental design for a combined telephone handset and desk stand, substantially as shown and described.
